UNITED STATES PATENT OFFICE.

CLARENCE J. WHITACRE, OF JANEVILLE, WISCONSIN, ASSIGNOR TO GENERAL MOTORS CORPORATION, OF DETROIT, MICHIGAN, A CORPORATION OF DELAWARE.

RADIATOR SHIELD FOR MOTOR VEHICLES.

Application filed June 17, 1922. Serial No. 569,105.

To all whom it may concern:

Be it known that I, CLARENCE J. WHITACRE, a citizen of the United States, and a resident of Janesville, county of Rock, 5 and State of Wisconsin, have invented certain new and useful Improvements in Radiator Shields for Motor Vehicles, of which the following is a full, clear, concise, and exact description, such as will enable 10 others skilled in the art to which the invention relates to make and use the same, reference being made therein to the accompanying drawings, which form a part of this specification.

15 My invention relates to motor driven vehicles, and particularly to the radiators of tractors and trucks; and the object thereof is to provide an improved foraminous metal shield or screen designed to overlie 20 the front end of the radiator core and to protect it from injury, as well also as to prevent leaves, trash, etc., from lodging upon the front exposed surface of the radiator core, which would act to impede 25 the flow of air therethrough. The principal object and effect of my invention, however, is to protect the comparatively frail radiator core structure from injury by external objects; to which end the screen or shield 30 is of strong construction, and is so held relative to the radiator core as to offer great resistance to forces which should they act directly upon the core would be likely to injure the same.

35 In the drawing accompanying and forming a part of this specification, and wherein the preferred embodiment of my invention is illustrated:

Figure 1 is a view showing a radiator of 40 a truck or tractor in elevation and as seen from a position in front thereof, the same being equipped with my improved radiator shield.

Figure 2 is a similar view in side elevation.

45 Figure 3 is a fragmentary view upon a larger scale showing certain details of construction of my invention, in front elevation.

50 Figure 4 is a similar view in side elevation.

55 Figures 5 and 6 are views similar to Figures 3 and 4, but showing my invention modified slightly as to some of the features thereof.

Referring now to the drawing, the reference numerals 10, 10 designate oppositely disposed side columns extending between upper and lower water chambers 11, 12 which are connected with the engine to be 60 cooled by suitable pipes 13, 14; the cellular core of the radiator being housed between the side columns, and the upper and lower ends thereof being in communication with the water chambers, so that the cooling 65 liquid may flow downward through the radiator; said water chambers serving to distribute the liquid cooling medium uniformly throughout the upper and lower ends of the cellular core structure to thereby 70 secure uniformity of flow through all parts of the core structure, all as is usual in radiator constructions. The cellular core structure is commonly made up of thin sheet metal bent to form passages for cooling 75 liquid, or comprises thin walled tubes through which the cooling liquid flows; and the same is a comparative fragile structure and one liable to injury from external objects coming into contact therewith. In the 80 radiator construction illustrated the core is provided with upper and lower headers or plates the peripheries of which are clamped between flanges 15, 16 of the water chambers and cooperating flanges at the ends of the 85 side columns 10, 10 by spaced bolts 17, although other constructions may be used as this present invention is in no way concerned with radiator construction per se.

My improved radiator guard or shield is 90 a foraminous structure shown as made up of vertical and horizontal wires 18, 19 interwoven with one another as is usual in wire or fabric articles; the outside wires 20, 21 being much heavier than the others and being 95 in fact rods or frames about which the ends of the horizontal wires are bent to thereby provide a strong structure. The upper and lower ends of the vertical wires 18 are held between the sides of U-shaped 100 strips of metal 22, 23 which, as said sides are flattened or pressed together, act to clasp and hold said ends; and act also to form smooth upper and lower frame members or edges for the guard.

105 My improved radiator shield is assembled with a radiator by curving it slightly and inserting the frame members or strips 22, 23, back of projecting portions, i. e., the heads or the nuts of the bolts 17, and between said 110

portions and the radiator core at the upper and lower ends thereof; after which the shield is flattened sufficiently to press the edges thereof into engagement with the 5 flanges 15, 16 along and just inside the rows of bolts, so that the strips 22, 23 extend along the joint between the upper and lower ends of the core structure and the water chambers when the shield is in place; the inherent 10 resilience of the screen being sufficient, ordinarily, to hold the upper and lower ends thereof in proper position between the bolts and the core after the screen has been curved slightly and properly put in place over the 15 radiator core.

The length of the shield may be such that it will be held in a slightly bowed position as shown in Figures 2 and 4, or it may be of such length that after having been put in 20 place it will lie substantially parallel with the front face of the core as shown in Figure 6.

Figure 6 shows also a modified form of peripheral frame wherein both the side and 25 upper and lower frame strips 24, 25 are formed by flattening the sides of U-shaped metal strips onto the ends of both the vertical and horizontal wires of the shield, thereby providing a smoother periphery 30 throughout than is the case in the form shown in Figures 1 to 4 wherein the ends of the horizontal wires are bent about the heavy side wires or rods 20, 21. The shield after having been finished and before it is 35 assembled with the radiator is commonly dipped into a suitable japan varnish bath to thereby provide a coating thereupon, or it may be galvanized or otherwise finished, as will be appreciated.

40 Having thus described and explained my invention, I claim and desire to secure by Letters Patent:

1. In combination, a radiator having an intermediate core, an upper water chamber 45 secured to said core by suitable fastening members, and a lower water chamber secured also to said core by suitable fastening members; and a foraminous shield or guard over-

lying the front of said core and the upper and lower edges of which extend along the 50 joints between said core and said upper and lower water chambers and are held in place by the fastening members whereby the water chambers and the core are secured together.

2. In combination, a radiator having an intermediate core, an upper water chamber secured to said core by spaced fastening bolts, and a lower water chamber secured also to said core by spaced fastening bolts; and a foraminous shield or guard overlying 60 the front of said core and the upper and lower edges of which extend along the joints between said core and said upper and lower water chambers and lie between projecting portions of said bolts and the radiator core.

3. In combination, a radiator having upper and lower water chambers provided with flanges, and an intermediate core section the 70 ends of which are secured to the flanges of said water chamber; and a foraminous shield or guard overlying the front of said core section and the upper and lower edges of which extend along and beneath and above the flanges aforesaid and lying in the angles 75 between said core section and said flanges.

4. A foraminous radiator guard or shield comprising horizontal and vertical wires spaced apart to provide openings; U-shaped metallic strips extending along the upper and lower edges of said guard, and enclosing the upper and lower ends of said vertical wires; and strengthening rods at the sides of said shield and the upper and lower ends of which extend into the strips 85 aforesaid, and to which the ends of said horizontal wires are connected.

5. A foraminous radiator guard or shield comprising interwoven horizontal and vertical wires spaced apart to provide openings; 90 and U-shaped metallic strips extending along the upper and lower edges of said guard, and enclosing the upper and lower ends of said vertical wires.

In testimony whereof I affix my signature.
CLARENCE J. WHITACRE.
